UNITED STATES PATENT OFFICE.

CLARENCE S. ELLINWOOD, OF CHICAGO, ILLINOIS, ASSIGNOR TO THE NATIONAL CASE REGISTER COMPANY, A CORPORATION OF OHIO, (ORGANIZED IN 1906.)

LEDGER-ACCOUNT FILE.

1,108,893.

Specification of Letters Patent.

Patented Sept. 1, 1914.

Application filed September 25, 1905. Serial No. 280,040.

To all whom it may concern:

Be it known that I, CLARENCE S. ELLINWOOD, a citizen of the United States, residing at Chicago, Cook county, Illinois, have 5 invented a certain new and useful Ledger- Account File, of which the following is a specification.

This invention relates to means for filing statements, bills or other evidences of account, more particularly a ledger account with the result that the ledger account of any customer may be readily and quickly ascertained and the ordinary books of account dispensed with.

15 According to the present embodiment of my invention the arrangement is such that the file will not only contain the statements or sales slips but also expose to view the ledger account of each customer whenever 20 such file is manipulated in the manner hereinafter described.

The various features of advantage and utility of the file will be apparent from the description hereinafter given.

25 In the drawing Figure 1 is a perspective of the ledger account file in one form of embodiment of the invention in which the same is shown as coöperating with a cabinet or filing case; Fig. 2 a central longitudinal 30 section of the forward portion of such file taken while in place in its cabinet or case; Fig. 3 a perspective of one of the series of partitions of the file; Fig. 4 a detail of one of the partitions; Fig. 5 a detail of a portion of the plate in which the partitions are pivoted; Fig. 6 an elevation of a modified form of arrangement of my account files; and Fig. 7 a sectional elevation of the account files of Fig. 6.

40 Referring to the present embodiment of the invention as herein illustrated, the same is formed as a drawer comprising a bottom 1, front 2, back 3, and parallel side-pieces 4, such drawer being arranged to be 45 inserted in an opening in a filing case such as the case 5 and in its preferred form adapted to coöperate with such filing case in the manner hereinafter explained. In this connection it will be understood that the 50 filing case is not essential to the invention considered in its broader aspect and also that the filing device may be employed singly or in series.

By preference and as herein shown the 55 front and back of the drawer are pivotally

connected to the bottom while the side-pieces or strips 4 are likewise pivotally connected at their ends to the front and back respectively, with the result that the front and back may swing to a position at an angle to the bottom in the manner illustrated in Fig. 1. It is desirable to limit the degree of movement of the front and back with respect to the bottom and to this end stops 6 are provided formed on or secured to the bottom and arranged to be contacted by the back 3, thereby stopping the latter as well as the front 2 through the medium of the connecting strips 4.

In the drawer and between the side-strips 4 is arranged a series of partitions 7 which are spaced apart at their lower and inner ends and thereat pivoted to the upper surface of the bottom of the drawer in any suitable manner. In the present instance 75 it is preferred to so pivot these partitions as to enable their ready removal or insertion in place, for which purpose each partition, which may be formed of thin sheet metal, is provided with one or more lateral 80 or right angled ears or lugs 8 which are arranged to be passed through one of a series of transverse slots in a plate 9 secured to the bottom of the drawer and positioned a slight distance above and parallel with the upper surface of the latter, as clearly indicated in Fig. 2. The result of this construction is that the partitions are pivotally connected to the bottom of the drawer and adapted to swing downwardly as seen in Fig. 1 and thereby to expose their respective front or back ends.

In order to space the upper ends of the partitions suitable means may be employed and as an economical construction distance pieces are formed by stamping tongues 10 from the body of the partitions themselves, such tongues projecting at right angles to the partitions and in the same direction, as seen in Fig. 2, thereby to space the upper ends of such partitions. By preference all or some of these partitions are provided with a pair of tongues 10 in order to form two bearings instead of one between adjacent partitions.

In Fig. 3 is shown a partition with the double tongues while in Fig. 4 is shown a portion of a partition illustrating the single tongue construction. When the two styles of partition are employed in the same

2
account file the single and the double tongue style may alternate. By reason of this construction the proper movement or sliding of the adjacent partitions as required in the manipulation of the account file is facilitated and improved, as will be understood from the explanation hereinafter made. The tongues 10, in the construction being described, constitute not only distance pieces but also stops for the lower edges of the account slips such as the slips A in Fig. 1, such edges being lowermost when the filing device is in its operative position as shown in Fig. 1 but becoming the upper edges when the filing device is in place in its case as in Fig. 2. Each partition is cut away on its right hand lower corner, substantially half-way of its width, so as to leave a projecting portion 11 at its lower left hand side or corner as clearly indicated in Figs. 1 and 3. This projecting portion is utilized for the purpose of indicating or bearing the indication of a customer's name and for the purpose of enabling such indication to be readily changed for different customers, it is preferred to provide such extending portion with a depression with parallel slits 12 through which a card bearing the customer's name may be passed and held suitably therein. As will be obvious the name may be indicated on the partition in any suitable manner as by impressing the name thereon, writing the same directly thereon or on a piece of paper or the like affixed thereto.

35 As hereinbefore stated the front 2 and back 3 of the drawer or account device are pivotally connected to the bottom 1 and such front and back are in turn operatively connected to each other by means of the parallel connecting strips 4 with the result that the movement of the front is communicated to the back and vice versa. Furthermore owing to this relative movement of the front and back with respect to the bottom of the drawer, the pivoted partitions 7 are enabled to take an angle or oblique position with respect to such bottom with the result that the outer or upper edges of the partitions will over-lap each other consecutively, in the manner clearly indicated in Fig. 1.

The account file being constructed as hereinbefore described, is operated and manipulated in the following manner: Assuming that a customer has bought a bill of goods, the items and amounts are written as usual on the original slip of a manifolding book of the usual and well known kind, and the total as usual is written in the lower right hand corner. This original slip which goes to the cashier or bookkeeper in the store is thereupon placed in the account file upon the partition which bears the name of the particular customer or purchaser of such bill of goods, it being understood that the superposed partitions are raised slightly by the

operator to permit the slip to be inserted therein and to take its place with its lower edge resting against the tongue or tongues 10 acting as stops. Each customer has his own space or compartment in the account file and the particular compartment is indicated by his name placed or affixed to the proper partition, in the manner already explained. The original slip for each purchase of goods ordered by different customers is placed in its proper compartment, in the manner above stated, it being understood that when these slips are in place and the account file is in its operative position indicated in Fig. 1 the outer edges of the partitions so over-lap each other consecutively as to expose the total or footing of each slip, in the manner indicated in Fig. 1. It is thus evident that the amount due from each customer can be ascertained at a glance inasmuch as the footing or total is exposed adjacent the customer's name. Assuming that a customer makes a second purchase before payment of the first purchase, the salesman, in addition to writing the items and amounts on the slip, will also examine the account file to ascertain whether there is any unpaid balance and if such is the case he will add such old amount or balance to the footing or total of the new items, which sum total will appear at the lower right hand corner of the slip. This second slip is now placed in its proper compartment and above the first slip with the result that said sum total, representing the full amount due from the customer is exposed to the operator. This process is repeated indefinitely, the account file being employed as a ledger which is always posted and is arranged to always exhibit the ledger amount due.

The account file is complete in itself when constructed as already described but as hereinbefore suggested, the same may be conveniently employed in connection with a file case or cabinet, in which event it is preferred to provide means for pivotally connecting the lower outer edge of the filing case with the lower inner edge at the rear end of the drawer, which may be accomplished in any suitable manner, with the result that the account file may be held suspended in an oblique position from the cabinet or filing case with the front 2 resting upon a desk or support as may be desired. According to the present construction, the inner end of the bottom of the drawer is provided with lateral projecting pins or trunnions 13 which are received within parallel tracks 14 extending horizontally and rearwardly into the opening in the filing case but closed at their front ends, with the result that when the drawer is pulled outwardly, the same is enabled to swing downwardly and is held by the closed ends of the tracks against entire removal from the filing case. The front 2 of

the drawer may constitute the closure of the opening in the filing case as indicated in Fig. 2, in which event such front or closure is provided with a lock or latch arranged to engage the filing case to hold the drawer locked or secured in place. In the present instance as indicated in Figs. 1 and 2 I have shown a spring latch 15 of this construction which may be adopted although a lock, such as a Yale lock for instance may be employed to securely lock up the account file against inspection by unauthorized parties.

As is evident the file possesses advantages over the usual ledger inasmuch as it always presents a posted account so that the amount of the ledger account or balance may be ascertained in an instant by simply glancing at the footing or total placed opposite the particular customer's name. Thus the account file not only possesses advantages over the usual ledger book but is adapted to displace such book and render the same entirely unnecessary, the bookkeeping being performed in fact by each salesman.

As hereinbefore suggested the filing case is not essential and the same as a matter of fact may be entirely dispensed with and the account file may thereupon be supported in any suitable manner and in any suitable position. To illustrate this a modified form of construction and arrangement is shown in Figs. 6 and 7 of the drawings in which Fig. 6 represents a front elevation of a series of the account files and Fig. 7 a sectional elevation. According to this construction the support 16, corresponding to the base or support 1 of the first described account file, forms the back of the file while the partitions 7, in this construction, are positioned normally obliquely, exposing the footings of the different accounts, that is the ledger accounts of the different customers. This file is also provided with a top 17 and a bottom 18 and also with a front closure 19 which may be employed if desired.

As illustrated in Figs. 2 and 7 the partitions are preferably provided with elastic bands 20 for the purpose of holding the tickets or slips in place on the partitions.

I claim:

1. An account file comprising a base having a front and a back pivoted thereto, a pair of parallel strips connecting said front and back, and a series of partitions pivotally mounted on said base.

2. In combination with a case or cabinet, an account file of drawer form received by the case and when pulled out arranged to be pivotally connected thereto, said account file comprising a base, a front and a back pivoted thereto, and a series of partitions arranged transversely of the base and pivotally mounted thereon.

3. An account file comprising a base, a plate secured to said base and having parallel slots, and a series of partitions having right angled ears passing through said slots and thereby pivoting said partitions. 65

4. An account file comprising a base, a supporting plate secured to said base, and having parallel slots, and a series of partitions comprising thin plates having projections extending at right angles to the plane of said plates, said projections passing through the slots in said supporting plate. 75

5. An account file comprising a base having a front and a back pivoted thereto, means connecting said front and back, stops for limiting the pivotal movement of said front and back, and a series of partitions 80 pivotally mounted on said base.

6. An account file comprising a base having a front and back pivoted thereto, a pair of parallel strips connecting said front and back, stops for limiting the pivotal movement of the front and back, and a series of partitions 85 pivotally mounted on said base.

7. In combination with a case or cabinet, of an account file of drawer form received by the case and arranged to be pivotally connected thereto when pulled out, said account file comprising a base having a front and a back pivoted thereto, stops for limiting the pivotal movement of the front and back, and a series of partitions pivotally 95 mounted on said base.

8. An account register comprising a series of normally superimposed and overlapping separators, a perforated hinge retaining plate, and one or more hinge members 100 projecting from one edge of each separator and through the perforations in said hinge plate whereby said members are hinged to said plate.

9. An account register comprising a tray, 105 a series of normally overlapping separators arranged in longitudinal rows, integral hinge members on one edge of each separator, and a hinge plate provided with apertures through which said hinge members 110 project, said plate being secured close to the bottom of the tray to bind said hinge members in position.

10. An account register comprising a plurality of separator plates having a plurality 115 of integral yieldable hinge members projecting from one edge thereof, and a hinge plate having apertures through which said hinge members project whereby said members are rigidly retained and the separator 120 permitted to swing in the register.
